1. A binding apparatus for loose leaf sheets, consisting of a sheet of paper having a binding margin, a coiled wire, and a binding strip, the sheet being provided with a series of small holes arranged in a row along the binding margin, the coiled wire being wound around the sheet and passing through the holes, the binding strip being attached to the coiled wire and being provided with a binding margin, the binding margin of the strip being removably fastened to the binding margin of the sheet.

LOOSE LEAF BINDING DEVICE

Frank Stanley Schade, Holyoke, Mass., assignor
to National Blank Book Company, Holyoke,
Mass., a corporation of Massachusetts

Application March 21, 1935, Serial No. 12,184

4 Claims. (Cl. 129—1)

This invention relates to improvements in loose leaf sheets and sheet binding mechanism. It is intended for use with that type of sheet binding mechanism which consists in a single helically coiled wire, successive turns of which pass through small holes arranged in a row along the binding margins of the sheets. These successive holes in the row are ordinarily spaced by the pitch distance of the coiled wire.

10 In the prior art binders of this coiled wire type, it is customary to thread the wire along the holes in the filler sheets and then provide a stop at the ends of the wires. The prior art book thus made is in effect a permanently bound book in the sense that the user does not ordinarily remove, replace, or insert sheets as in a loose leaf book. While it is possible to remove the stops at the end of the binding wire and unscrew the coiled wire from binding relation 20 to the sheets, arrange the sheets and again screw in the binder, it takes altogether too much time, work and care to do this. So the custom is to bind the sheets at the factory and the user handles the book as he would a permanent- 25 ly bound one.

According to one feature of my invention I make my sheets for a binder of the type mentioned, but with novel structure so arranged that the user may have a loose leaf book in which 30 individual sheets can be very conveniently removed, put in, or interchanged in the filler pack as in loose leaf books. My means for this purpose has a different structure and mode of operation from prior art loose leaf books, so far 35 as I know.

According to another feature of my invention I combine the coiled wire binding means with a pack of narrow binding strips instead of filler sheets. These strips are so made that they can 40 be easily fastened and unfastened individually to the coiled wire and they are particularly adapted for the user to permanently attach any desired type of filler sheet to the strips, as by pasting overlapped binding margins together and 45 having the strips give the desired cooperation with the binding means.

Other features of the invention will appear in the detailed description of the accompanying drawings and in the claims.

50 In the drawings:

Fig. 1 is a plan view with part cut away of a binder with the coiled wire binding means there- 55 in but without any sheets or leaves;

Fig. 2 is a plan view of a filler sheet with means

on, the binding margin for removably fastening it to the coiled wire;

Fig. 3 is an enlarged scale end view of the sheet with a part beyond the binding margin cut away;

Fig. 4 is a plan view of one binding strip made for attachment of a filler sheet;

Fig. 5 is a perspective view of a book with a pack of binding strips mounted therein, a part of the book being cut away to save space; and 10

Fig. 6 is a view to indicate the progress of a sheet as it is being put in or taken out of the book.

Fig. 1 shows one customary type of coiled wire binder with the wire 1 and covers 2 and 3 hung thereon, but with no filler sheets. Fig. 2 shows an example of one of the filler sheets 4 made according to my invention. It consists of any type of paper portion 5, and that type may be thin book paper such as used for writing in loose leaf books. To make the filler sheet in a preferred way, I moisten the binding margin of paper 5 with a solvent for celluloid, lay a strip of celluloid 6 along the moistened margin and press the two together with a heated roll 25 or presser bar. The solvent and heat cause the celluloid to soften enough to make an exceedingly strong adhesive contact between the strip 6 and paper 5. Of course the strip could be of other material and the permanent contact made with the paper in other ways. The object is to get a relatively strong springy binding reinforcement on the paper sheet. And this can be done in various other ways, for example by a strip of metal foil applied with 30 thermo-plastic cement. I prefer to have the reinforcing strip of as thin material as practical so long as it has the flexible and stiffening functions of a wear strip such as I will 35 describe.

The holes 7 are provided in the binding margin of the sheet and through the superposed paper and celluloid. I make a cut 8 from each hole 7 directly out to end through the binding edge of the sheet margin. I also make a cut 45 9 from the edge of the binding margin and at right angles thereto between each pair of holes 7. The result is that each hole 7 is located within the area of a small rectangular flap. Each flap has a flexible integral hinge connection or binding line 10 with the celluloid strip. The latter is stiff enough and the construction is such that there is a strong tendency for all the flaps with the holes 7 therein to lie perfectly flat in the plane of the strip and filler 50 55

sheet. But the flaps may be deliberately and individually bent out of that plane, when desired. I prefer to make the cuts 8 and 9 without substantial width rather than as slots, although the latter may be used in the broader aspects of my plan.

To fasten the sheet 4 on the coiled binding wire 1, the sheet margin is started by pushing the end convolution sidewise through the end cut 8. 10 Then the margin is bent into place so that each successive cut 8 admits each wire convolution as the sheet is laid against the coiled wire. This operation is indicated in progress from bottom to top of Fig. 6. The parts can be assembled with 15 convenience by overlaying the wire coil at the side with the binding margin of the sheet and by pressing the sheet down against the wire as by running the finger against the sheet along a line just back of the row of holes. The pressure 20 causes the flaps to bend and tip enough for the end of the cuts 8 to find the sides of the wire convolutions and admit them through the cuts to holes 7 one after the other. As soon as the wire turns are located in holes 7 the flaps will 25 return to their normal flat position by the strong flattening tendency of the celluloid flap.

To unfasten the filler sheet from the binder it is only necessary to pull the sheet from the upper right-hand corner just as if one were tearing the 30 sheet out of the book. In the action each flap half is bent to snap over its wire so as to free the latter from the retaining hole. The wire rides out through the cut 8 and continued "tearing" pull on the sheet unfastens one convolution 35 after another. The action is about as fast as if one were tearing out a sheet off an integral stub along a line of perforations. But in this case the wire 1, instead of a stub, separates through cuts 8 exactly located for the purpose 40 and there is no tearing. The fastening of the sheet 4 on the wire 1 is simply the reverse bending movement from that of pulling it off and the operator's finger can be slid along back of the line of holes with a pressure action which is the 45 reverse along that line of the pulling action as in the tear.

One important function of the cuts 9 is to confine the pulling and pushing action adjacent each hole to the flap of that hole. This substantially avoids the transmission of the pulling or pushing forces in the operations from one flap to the adjacent flap. The consequence is that each flap action is independent with respect to the bending necessary for the wire binder construction to snap into or out of the one hole of its adjacent flap. In the absence of cuts 9 the flap bending line would be the line connecting two adjacent holes. The flap could not be bent without affecting the conditions at both holes. 50 I prefer not only to use the cuts 9 to avoid the bending action on the line between two holes but also to have cuts 9 long enough to locate the flap bending line back of the line between the two holes as I have indicated. This provides in the 55 best manner I know for making the flap action individual with respect to the hole. Even though binding wire 1 is made of small gauge wire, it has some thickness, so that as one coil crowds through one cut there is a necessary bending in 60 the flap area to admit the wire to the hole. After it gets in the hole the fit is loose and when the next wire is crowded through its cut it may not be lined up to do so as well as the previous coil did. But with the flaps cut as at 9 the flap halves 65 adjacent the holes 7 work around the thickness

of the wire without any objectionable strain that might make successive actions between wire and binding margin harder to accomplish. The fact is that the desired action with my preferred form is accomplished in a remarkably easy fashion. 5

I have described the binder and the action with one filler sheet 4. I make up my improved loose leaf book with a pack of filler sheets fastened and unfastened in the same way. This gives me a whole book with all the advantages of the ordinary coiled wire binder over the customary ring type binder such as are generally recognized by users. Heretofore, the ring binder book has had the advantage in the easy removability and insertion of individual sheets which the coiled 15 binder lacked. My improved coiled wire binder now has the same loose leaf book advantage and with a remarkably effective structure for attaining the advantage of both types of books.

So far as I know, manufacturers have not 20 heretofore sold for general use the coiled wire binder without the filler sheets. The customary type of binder did not permit this practice, but with my improvements this can now be done. The casual user can buy his binder and select his 25 desired type of filler sheets for insertion all with the same convenience as in ring binder casual customer's practice.

The ordinary user of loose leaf books frequently wants to bind up special sheets of his 30 own which are not practical to supply through a stationery store. An example is the desire to bind up patent copies in loose leaf form. I have extended my present invention to a structure to fill this need. The modification is shown in Fig. 35 4. In addition to making filler sheets at the factory to bind in my improved way, I plan to make filler strips or stubs 11 as shown. The celluloid 6 is fastened as a reinforcement to a slightly wider paper strip 12 in the way already 40 described. The paper extends sidewise of the celluloid enough to provide a pasting strip. This pasting strip extension is preferably provided on its face with a layer of adhesive gum indicated at 13. A patent copy can be separated by pulling 45 out the binding staples. Each sheet can be pasted on the special stub 11 along the binding margin and then the stub put in my binder. A book can be made up in this way by anyone, containing a desired set of patent copies with the binding structure of Fig. 5, and it is a most convenient way to do it, superior to any available 50 and customary loose leaf form for the purpose, of which I am aware. The value in the use is that there is a better binding structure with the 55 coiled wire type, since the sheets of a book may be turned over so easily that the book can be opened back to back. With my sheet removability feature, the drawing of a patent copy can be laid alongside of its description by the individual handling of the sheets, no matter how they were originally bound in the book. Patent copies are notoriously inconvenient to handle and bind in loose leaf form in part because to examine the drawing while reading the description extending 60 over opposite sides of a single page requires so much turning. Furthermore, the paper is not of a grade that works well with punched holes or ring binders when the copy sheets are loosened and separated from their original staple 65 binding means. My modification is particularly adapted for good utility under such adverse conditions in the paper sheets to be bound.

Having disclosed my invention, I claim:
1. A loose leaf structure formed of sheet ma-

- terial including a stiff, springy binding margin provided with a row of holes for the reception of the turns of a helically wound binding wire, hole entering cuts extending from each hole to and through the binding edge of said binding margin, and cuts positioned intermediate said holes and extending inwardly from said binding edge a distance sufficient to enable the material between the intermediate cuts and the hole entering cuts to be temporarily flexed from the plane of the sheet, to permit the turns of the binding wire to enter and leave the holes by way of the hole entering cuts, without impairment to the resistance of the material adjacent the holes to tearing or distortion from contact with the wire in the normal use of the structure.
2. A loose leaf structure formed of sheet material including a stiff, springy binding margin provided with a row of holes for the reception of the turns of a helically wound binding wire, hole entering cuts extending from each hole to and through the binding edge of said binding margin, and cuts positioned intermediate said holes and extending inwardly from said binding edge to a bending line beyond the holes forming individual tabs for each hole thereby enabling each tab to be temporarily swung out of the plane of the sheet and enabling the material between the intermediate cuts and the hole entering cuts to be temporarily twisted out of the plane of the tabs, to permit the turns of the binding wire to enter and leave the holes by way of the hole entering cuts, without impairment to the resistance of the material adjacent the holes to tearing or distortion from contact with the wire in the normal use of the structure.
3. A book with exchangeable leaves comprising in combination loose sheets, each sheet having perforations near its binding edge, slits extending from each perforation to said edge and affording entrance to the perforations from said edge, tab forming slits between adjacent perforations, and a helically wound wire the distance between the turns of which corresponds to the distance between said perforations, said wire having one turn extending through each of said perforations, said wire being adapted to have the respective turns thereof inserted and removed from the perforations by way of said first named slits upon flexing of the tabs from the plane of the sheet and the flexing of the portions of the tabs adjacent the first named slits out of the plane of the tabs.
4. The combination of a strip of flexible springy thin material and a strip of paper adhesively fastened thereto and extending beyond one side edge thereof, adhesive gum on the extended surface of said paper, a row of spaced holes along the opposite edge of the springy material for the reception of the turns of a helically wound binding wire, cuts intermediate the holes to arrange each hole in an independent tab and cuts affording sidewise entrance to said holes through which the turns of said wire may enter and leave the holes by flexing of the tabs from the plane of the strip and the flexing of the portion of the tabs adjacent the entrance cuts from the plane of the tabs.
